F. B. LITTLE.
SWITCHING MECHANISM.
APPLICATION FILED FEB. 25, 1916.

1,216,238.

Patented Feb. 13, 1917.

UNITED STATES PATENT OFFICE.

FREDERICK B. LITTLE, OF CHICAGO, ILLINOIS, ASSIGNOR, BY MESNE ASSIGNMENTS,
TO J. C. DEAGAN MUSICAL BELLS, OF CHICAGO, ILLINOIS, A CORPORATION OF
ILLINOIS.

SWITCHING MECHANISM.

Specification of Letters Patent. Patented Feb. 13, 1917.

1,216,238.

Application filed February 25, 1916. Serial No. 80,327.

To all whom it may concern:

Be it known that I, FREDERICK B. LITTLE, citizen of the United States, residing at Chicago, in the county of Cook and State 5 of Illinois, have invented a certain new and useful Improvement in Switching Mechanism, of which the following is a full, clear, concise, and exact description, reference being had to the accompanying drawings, 10 forming a part of this specification.

My invention relates to switching apparatus and finds a very important use when employed for controlling the operation of electro-magnetically actuated sound producing or other responsive devices that are 15 to be operated when the keys of a keyboard musical instrument are manipulated to furnish accompaniment for the music produced by the keyboard instrument. The invention, 20 however, is not to be limited to any particular use to which it is put.

One feature of the invention resides in a switch having stationary and movable contacts, a rotatably mounted stem for the moving contact which is of arc-shape to cause 25 rapid actuation of the moving contact when the switch is located close to the pivotal mounting of the musical instrument key that is to operate it. A spring is employed 30 to cause the curved key engaging portion of the stem to follow the key when depressed to close the circuit, the "action" controlled by the key serving, in restoring the key, also 35 to restore the moving contact against the force of the aforesaid spring.

Another feature of the invention resides 40 in the provision of a conduit, preferably trough shaped, and U-shaped frames upon which the stems of the movable contacts are pivotally mounted and upon which frames 45 the springs are mounted which cause the stems to follow the keys to which they are individual. These frames are provided with 50 means for removably securing them in assembly with the conduit while the conduit is provided with formations that serve to locate the frames thereon whereby the switches may be properly spaced with respect to the keys with which they are to operate.

I will explain my invention more fully by 55 reference to the accompanying drawing showing the preferred embodiment thereof and in which Figure 1 is a cross sectional view showing switching mechanism of my

invention and its application to the keyboard instrument, a responsive device individual to this switching mechanism being diagrammatically indicated in circuit relation therewith; Fig. 2 is a plan view, partially in section, illustrating a plurality of switches in assembly and each individual to a key underlying the same; Fig. 3 is a perspective view illustrating the preferred form of stationary contact entering into the 60 preferred construction; Fig. 4 is a perspective view of the complete switch; and Fig. 5 is a perspective view of a portion of conduit illustrating the formation by which 65 the switches may be definitely located with 70 respect to each other.

Like parts are indicated by similar characters of reference throughout the different figures.

The keys 1 and 2 may, for the sake of 75 illustration, be considered to represent respectively the black and white keys of a piano. No other part of a piano action is illustrated, there being a diagrammatic representation of a spring at 3 to indicate an 80 agency for restoring each key when the pressure thereupon is released, this function being performed by this action as is well understood by those skilled in the art. The 85 keys are pivotally mounted near the rear of the exposed portions thereof as indicated at 4, the riser or vertical panel 5 of the cabinet being disposed slightly in advance of the key pivots. The conduit 6 is desirably of 90 trough formation and is supported at its 95 ends upon pedestal blocks 7 that may rest upon the piano cabinet at the ends of the keyboard, the pedestals and the conduit they support being readily removed when it is desired to dissociate the switching mechanism from the piano. The conduit is provided with formations, desirably in the form of recesses 8, that are spaced apart longitudinally of the conduit distances corresponding to the arrangement of the keys, these recesses receiving the bases of the inverted U-shaped frames 9 to prevent movement of these frames lengthwise of the conduit whereby these frames are positioned over the keys when the pedestals 7 are in position. 100 Each frame 9 carries a rearwardly extending ear 10 upon which is pivoted the stem 11 carrying the contact blade 12' at its upper end and being of arc-shape at its lower end where it engages the key that underlies 110

such frame. This frame also carries a leaf spring 12 that serves to press the stem 11 upon the underlying key and to maintain substantially constant engagement between this stem and the key whereby when such key is depressed such spring is effective to enter the blade 12 into engagement with and between the leaf contacts 13 which are also desirably mounted upon but are insulated from the frame 9 whereby a unitary structure is produced as illustrated most clearly in Fig. 4, the rear side of the frame carrying the movable contact while the front side of the frame carries the stationary contact. The holding screw 14 passes through the front side of the frame into engagement with the curved bottom of the conduit whereby the frame is maintained in assembly with the conduit 6. It will be observed that, although the stems 11 engage the keys close to the key mountings, yet the switch will be properly operated since the arc-shaped stem will sufficiently increase the movement of the contact blade in proportion to the movement of the part of the key engaging the stem of the blade to cause the proper operation of the switch while at the same time allowing sufficient portions of the keys to project beyond the switching mechanism to be suitably manipulated by one who wishes to play the piano manually. To avoid noise each stem 11 has a bottom face of felt 15 where it engages the underlying key.

35 The responsive devices illustrated include mechanism which form the subject matter of my co-pending application Serial No. 80,328, filed February 25, 1916, and executed of even date herewith. These responsive devices include sounding bars 16 arranged to produce the tones of a musical scale, resonators 17 being located to the rear of these bars. Each bar has a hammer 18 carried by the armature 19 of an electro-magnet 20, there thus being one such electro-magnet for each bar. The circuit for each magnet includes the stationary contact 13 individual thereto, the armature controlled contacts 21 and 22, the winding of the magnet 20, the battery 23 common to all magnets 20, the switch 24, the frame 9 carrying the contact 13 but insulated therefrom, the stem 11 carried by such frame, and the blade 12 carried by such stem. There may be but a single or common connection between the battery 23 and the frames 9 as I prefer electrically to connect all frames by means of the metallic conduit 6 whereby all the switch blades 12 are in common connection with each other. The switch 24 is included in such common connection and may be thrown to open position whenever it is desired temporarily to throw the switching apparatus out of service. Conductors 24 extend from the other side of the battery 23 to the vari-

ous magnets 20. The conductors that are individual to the stationary contacts 13 are laid in the conduit 6 and project from this conduit wherever they are to be attached to these contacts.

70 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. Switching mechanism including a conduit for electrical conductors that are connected therewith; mounting frames separably connected with the conduit; stationary contacts carried by the frames; and contacts pivotally mounted upon the frames and complementary to the stationary contacts. 80

2. Switching mechanism including a conduit for electrical conductors that are connected therewith; mounting frames separably connected with the conduit; stationary contacts carried by the frames; and contacts pivotally mounted upon the frames and complementary to the stationary contacts, the conduit having formations for engaging the frames to prevent movement of the frames longitudinally of the conduit. 90

3. Switching mechanism including a conduit for electrical conductors that are connected therewith; mounting frames separably connected with the conduit; stationary contacts carried by the frames; contacts pivotally mounted upon the frames and complementary to the stationary contacts; and securing means for separably securing the frames and conduit together. 100

4. Switching mechanism including a conduit for electrical conductors that are connected therewith; mounting frames separably connected with the conduit; stationary contacts carried by the frames; contacts pivotally mounted upon the frames and complementary to the stationary contacts, the conduit having formations for engaging the frames to prevent movement of the frames longitudinally of the conduit; and securing means for separably securing the frames and conduit together. 110

5. Switching mechanism including a conduit for electrical conductors that are connected therewith; U-shaped mounting frames separably connected with the conduit that is received between the sides of the U-shaped frames; stationary contacts carried by the frames; and contacts pivotally mounted upon the frames and complementary to the stationary contacts. 120

6. Switching mechanism including a conduit for electrical conductors that are connected therewith; U-shaped mounting 130

frames separably connected with the conduit that is received between the sides of the U-shaped frames; stationary contacts carried by the frames; and contacts pivotally mounted upon the frames and complementary to the stationary contacts, the conduit having formations for engaging the frames to prevent movement of the frames longitudinally of the conduit.

10 7. Switching mechanism including a conduit for electrical conductors that are connected therewith; U-shaped mounting frames separably connected with the conduit that is received between the sides of the U-shaped frames; stationary contacts carried by the frames; contacts pivotally mounted upon the frames and complementary to the stationary contacts; and securing means for separably securing the frames and conduit together.

8. Switching mechanism including a conduit for electrical conductors that are connected therewith; U-shaped mounting frames separably connected with the conduit that is received between the sides of the U-shaped frames; stationary contacts carried by the frames; contacts pivotally mounted upon the frames and complementary to the stationary contacts, the conduit having formations for engaging the frames to

30 prevent movement of the frames longitudinally of the conduit; and securing means for separably securing the frames and conduit together.

9. A switch including a mounting; a stationary contact carried by the mounting; a second contact pivotally supported upon the mounting and complementary to the aforesaid contact, the second contact having a stem projecting upon one side of the pivot 40 while the contact to which the stem belongs is disposed upon the other side of the pivot, the end of the stem remote from the contact connected therewith underlying the contacts and the mounting therefor and being 45 of arc-shape; a key pivotally mounted near the stem and engaging the arc-shaped end thereof; and a spring for substantially maintaining engagement between the arc-shaped end of the stem and the key. 50

In witness whereof, I hereunto subscribe my name this 17th day of February, A. D., 1916.

FREDERICK B. LITTLE.
